UNITED STATES PATENT OFFICE.

HENRY D. STAUFFER, OF OREGON, ILLINOIS.

INSULATOR.

No. 854,315.

Specification of Letters Patent.

Patented May 21, 1907.

Application filed July 24, 1905, Serial No. 270,974.

To all whom it may concern:

Be it known that I, HENRY D. STAUFFER, a citizen of the United States, residing at Oregon, in the county of Ogle and State of Illinois, have invented certain new and useful Improvements in Insulators, of which the following is a specification.

The object of this invention is to construct an insulator for electrical line wires and consists of two metallic sections, each supporting a section of insulating material and each section of insulating material supporting a metallic plate between which the line wire is received, and means for clamping the opposite metallic sections together.

In the accompanying drawings Figure 1 is an isometrical representation of my improved insulator. Fig. 2 is a vertical transverse section.

20 The lower section 1 of the insulator is in semi-cylindrical form tapering toward the ends. The upper surface of this lower section is hollowed out and within the cavity is located a porcelain body 2 having its upper 25 face recessed, and within the recess is located a metallic plate 3 having its upper face provided with a lengthwise semi-circular groove 4, having its bottom serrated. From the upper face of the lower section extends a rib 30 5 along the two sides thereof. From one edge of the lower section extends a flange 6 having a screw threaded opening 7. From the other edge of the lower section extends a 35 perforated ear 8. The under face of the lower section has a screw threaded opening 9.

A shank 10 has its upper end screw threaded and is located in the screw threaded opening of the lower section. The lower end of this shank is screw threaded to receive a nut 40 11. The upper end of the shank 10 has an enlargement 12 and from its lower face extends two prongs 13.

The upper section 14 of the insulator is identical with the lower section so far as relates to the porcelain center 15 and the metallic plate 16. The underface of the upper section has a groove 17 along its sides, which is of a size and depth to receive the ribs 5 of the lower section. From one edge of the 45 50 upper section extends a perforated ear 18, and from the other edge of the upper section

extends two lugs 19 from which extends the covering 20. These lugs 19, in connection with the ear 8 of the lower section, through which extends a pintle 21, form a hinge connection between the two sections of the insulator, and the covering 20 extends over the hinge and protects it from the rain. The lower end of the shank is placed in an opening in the cross arm. The prongs 13 are 60 driven into the cross arm and the shank is held in connection therewith by the nut 11. The lower section of the insulator is turned in connection with the upper screw threaded end of the shank. A line wire 22 is placed in 65 the semi-circular groove in the lower section, and the upper section of the insulator is turned over the lower section and held there by the thumb screw 23 passing through the opening in the flange of the upper section 70 into the screw threaded opening 7 in the flange of the lower section. As the grooves of the plates 3 and 16 are roughed or serrated the wire will be held firmly in contact therewith. It will be noticed that the ends of the 75 plates 3 and 16 are cut away or beveled, which permits the line wires to move laterally a given distance and also prevents water from entering between the sections of the insulator. By the employment of my improved insulator the line wires can be quickly clamped in place in connection therewith and can be easily removed therefrom. The porcelain sections 2 and 15 prevent the grounding of the wires.

It is evident that glass or other suitable insulating material may be employed in place of the porcelain and still be within the scope of my invention.

I claim as my invention.

An insulator comprising two halves hinged together, means for connecting their free edges, their meeting faces—each having a section of insulating material fixedly connected thereto and each section of insulating material having a metallic plate fixedly connected thereto.

HENRY D. STAUFFER.
